UNITED STATES PATENT OFFICE

108,454

DESIGN FOR A SERVICE STATION DISPLAY CASE OR THE LIKE

Ralph O. Munson, Chicago, Ill., assignor to Standard Oil Company, Chicago, Ill., a corporation of Indiana

Application December 24, 1937, Serial No. 73,852

Term of patent 7 years

To all whom it may concern:

Be it known that I, Ralph O. Munson, a citizen of the United States, residing at Chicago, in the county of Cook and State of Illinois, have invented a new, original, and ornamental Design for a Service Station Display Case or the Like,
of which the following is a specification, reference being had to the accompanying drawings, forming part thereof, in which:

Figure 1 is a front elevational view of a service station display case or the like, showing my design;

Figure 2 is a top plan view thereof; and Figure 3 is a front perspective view thereof, on a reduced scale.

I claim:

The ornamental design for a service station
display case or the like, substantially as shown.

RALPH O. MUNSON.
